Primary Examiner — Holly Bayham(74) *Attorney, Agent, or Firm* — Avery Dennison Corporation(57) **CLAIM**

The ornamental design for pouch with applied tape, as shown and described.

DESCRIPTION

FIG. 1 is an isometric view of multiple tape strips on a pouch showing our new design;

FIG. 2 is a front of FIG. 1;

FIG. 3 is a back view of FIG. 1;

FIG. 4 is a left view of FIG. 1;

FIG. 5 is a right view of FIG. 1;

FIG. 6 is a top view of FIG. 1; and,

FIG. 7 is a bottom view of FIG. 1.

The broken lines showing a pocket are for the purposes of illustrating environment and form no part of the claimed design.

1 Claim, 3 Drawing Sheets(56)
